ICE-FORMING AND ICE-MELTING
COOLING SYSTEMJoseph I. Morrison, Lincolnwood, Ill.; Grace F. Morrison
and John O. Levinson, executors of said Joseph I. Mor-
rison, deceasedFiled Aug. 6, 1954, Ser. No. 448,245
1 Claim. (Cl. 62—435)

This invention relates to cooling systems and, more particularly, to a cooling system for use in a commercial dairy and the like where the cooling demand is variable.

One of the objects of the invention is to provide improved apparatus for controlling the rate of formation and melting of ice on a temperature-controlled plate, as the congealable liquid flows over the surface of the plate, by means of bars interposed in the path of the liquid flow for agitating the liquid, extending substantially parallel to each other and to the plate.

It is a further object of the invention to provide a cooling system which is simple and compact in construction, effective and efficient in operation, and inexpensive to produce.

Further and additional objects will appear from the description, the accompanying drawings, and the appended claims.

For a more complete understanding of this invention, reference should be made to the drawings, wherein

FIGURE 1 is a longitudinal vertical section of a tank divided into compartments containing the flowing liquid, cooling coils, plates, etc.

FIG. 2 is a horizontal section substantially on the line 2—2 of FIG. 1 showing the flow-guiding plates or baffles, the cooling coils and plates and the turbulence-creating bars in the path of the liquid flow;

FIG. 3 is an end view of FIG. 1, viewed from the left;

FIG. 4 is a side elevation showing the fluid agitating ladder-like lattice construction of FIGS. 1 and 2;

FIG. 5 is a diagrammatic perspective view showing the flow direction of FIGS. 1 and 2;

FIG. 5a is a perspective view of a lattice construction of chain supported liquid-agitating bars;

FIG. 6 is a vertical sectional view on the line 6—6 of FIG. 7, of a construction showing another embodiment of my invention, providing for generally vertical or upright flow of the congealable liquid;

FIG. 7 is a vertical section on the line 7—7 of FIG. 6;

FIG. 8 is a perspective view showing a lattice construction of liquid-agitating bars;

FIG. 8a shows cross-sectional view of different types of liquid-agitating bars which may be found desirable. Some of these bars may, if desired, be tubular in cross section. The sections shown include circular, rectangular, parallelogram, T-sections and angle sections. They may also include bars twisted to provide helically extending edge portions;

FIG. 9 is a plan view showing another form of lattice construction in which the sections of the lattice have a hinged connection with each other to enable folding;

FIG. 10 is a side elevational view showing the lattice sections folded;

FIG. 11 is a diagrammatic fragmentary view of the ice builder of FIGS. 6 and 7, with a portion shown in vertical section of the baffles and lattice construction, and

FIG. 12 is a diagrammatic plan view showing eight vertically extending lattice-like ladders suspended in vertical position in the tank.

The construction shown comprises a freezing and ice-melting cooling apparatus comprising two juxtaposed refrigerant-receiving and heat-transferring devices, each provided with an extensive heat-transfer surface, said surfaces being substantially parallel to each other, and means

2

for causing a flow of congealable liquid in the passage between said surfaces, whereby the liquid may be congealed on said surfaces by the refrigerant and may be melted therefrom by the flow of the liquid, said surfaces being provided with a series of bars extending across the passage intermediate said surfaces and substantially parallel to each other and to said surfaces to increase the turbulence of liquid passing through said passage.

Referring now more specifically to the drawings and first to FIGS. 1 to 5 inclusive, a reservoir 10 is shown, which is operatively connected by suitable conduits 12 and 14 to an adjacent cooling tank 65. Intermediate the cooling tank and reservoir 10 is provided a suitable pump 16a, for circulating a cooling liquid through the reservoir and cooling tank.

Mounted within the reservoir 10 are a plurality of parallel, vertically-extending, spaced flow-directing and heat-transferring baffle members 16 and 18, and a horizontally-extending transversely mounted flow-directing baffle member 20 dividing baffle members 16 and 18 into substantially equal sections 16a, 16b, 18a and 18b. The baffle members 16, 18 and 20 are so arranged within the reservoir as to cause the direction of flow of the circulating liquid to be like that shown in FIG. 5.

The relatively warm liquid from the cooling tank enters the reservoir through conduit 12 and first passes, as shown in FIGS. 2 and 5, between the side 21 of the reservoir and baffle member 18a and, upon reaching the terminating edge 22a of member 20, which is spaced from the end plate 23 of the reservoir, is directed downwardly and flows in the opposite direction between side 21 and baffle member 18b; on reaching the edge 24 of member 18b, which is spaced from the end plate 25 of the reservoir, the liquid turns about edge 24 and flows in the

opposite direction between baffle members 16b and 18b; on reaching the edge 22b of baffle member 20, the liquid is directed upwardly and flows in the opposite direction between baffle members 16a and 18a; upon reaching the terminating edge 26 of baffle member 16a, which is likewise spaced from end plate 25, the liquid reverses direction and flows between side 27 of the reservoir and baffle member 16a; at terminating edge 22c of member 20, the liquid once again is directed downwardly and flows in the opposite direction between side 27 and baffle member 16b and out through conduit 14 to the cooling tank, not shown. By following this tortuous passage through the reservoir, the circulating liquid is able to expend a sufficient amount of heat to readily meet the variation in cooling demand.

The two vertically disposed heat transfer plates 16 and 18 and the horizontally disposed flow guide plate 20 divide the tank into six sections, providing for a flow in series from the entrance opening 12 to the exit passage 14. The flow is shown diagrammatically by the arrow position and direction indicated in FIGS. 1, 2 and 5. As indicated there the flow is from the inlet pipe 12 along the forward front passage to the right-hand end of this passage, thence downwardly past the edge of the plate 20 to the lower forward passage, thence to the left along this lower forward passage, thence rearwardly from the left-hand end of this passage to the right-hand end of the intermediate passage, thence upwardly past the plate 20 to the upper righthand end of the intermediate upper flow passage, thence along this upper intermediate passage to the right-hand end of the intermediate passage, thence rearwardly to the upper left-hand end of the rear passage, thence to the right-hand end of the rear passage, thence downwardly to the lower right-hand end of the rear passage, thence to the left and along this lower rear passage to the outlet pipe 14.

A refrigerator 28 is provided for the reservoir having a plurality of refrigerant-receiving and heat-absorbing as-

semblies 30 and 32. Assembly 30 is mounted on one surface of baffle members 16a and 16b, and assembly 32 is mounted on a corresponding surface of baffle members 18a and 18b. In this instance, each assembly comprises banks of coils integrally connected to one another and each assembly 30 and 32 serves as a refrigerator for baffle members 16a, 16b and 18a, 18b, respectively. The refrigerant supply, the means for circulating the refrigerant through the coils, and the compressor for the refrigerator are of standard construction and well known by those skilled in the art and, therefore, further discussion as to their operation is deemed unnecessary. The refrigerant, which may be ammonia, sulphur dioxide, etc., is introduced, as shown by arrow A, FIG. 3, into the cooling coils 30 and 32 in a liquid form from the expansion valve, not shown, through conduits 34 and 35, respectively, and is removed from the coils, as shown by arrow B, in a gaseous state at conduits 36 and 37, respectively, to the compressor, not shown.

Mounted on either face of the baffle members 16a, 16b, 18a, and 18b, and on the inner surfaces of sides 21 and 27 of the reservoir are a plurality of finlike members 40. These members 40 are constructed of relatively thin, rigid material, such as sheet metal, and as shown in FIGS. 1 and 4, are of rectangular shape. The members 40 are spaced from one another along the surface of the flow-directing, heat-transferring baffle members 16a, 16b, 18a, and 18b, and extend in substantially a vertical direction. The vertical plane of the members 40 are offset approximately 30° with respect to the adjacent baffle member to which they are secured.

The liquid agitating lattice construction shown in FIG. 4 comprises a plurality of vertically extending liquid-agitating bars 41 connected at their upper and lower ends to longitudinally extending beams 42 and 43, the upper one 42 of which is provided with hooklike extensions 44 for fastening over the upper edges of the ends of the tank. It will be noted that these lattice sections are provided only in the upper tier of coil compartments where one can easily increase or lessen the number of sections to accomplish the necessary agitation to properly control the melting of ice therefrom.

In the installation of ice-forming and ice-melting cooling system of the type having no guiding and agitating louver constructions or of the type in which such louver constructions are somewhat permanently installed, it may sometimes be found necessary or desirable to provide additional cooling effects. This may be accomplished in applicant's construction by means of the lattice-like flow-agitating bars which may be readily placed in position in installations already made. This additional flow-agitating cooling effect may be obtained both in the construction shown in FIGS. 1-5, incl., and that shown in FIGS. 6-12, incl. It will be noted that both the construction of FIGS. 1-5, incl., and that of FIGS. 6-12, incl., disclose improved apparatus for controlling the rate of melting of ice on a temperature-controlled plate, as the congealable liquid flows over the surface of the plate, by means of bars interposed in the path of the liquid flow for agitating the liquid, extending substantially parallel to each other and to the plate.

The greater the agitation caused by the interposed bar the greater will be the impact of the relatively warm fluid on the ice coating, the faster will be the melting of the ice coating, and the faster will be the cooling of the fluid in the reservoir.

In the embodiment of the invention as shown in FIGS. 6 to 12, inclusive, the flow of the circulating liquid is substantially in a vertical direction rather than in a horizontal direction as shown in FIGS. 1 to 5, inclusive. In this embodiment also liquid-agitating bars (shown in FIGS. 8 and 8a) similar in effect to the bars 41 of FIG. 4 may be used. In place of the cooling coils of reservoir 10 there are provided in reservoir 48 a plurality of vertically extending conduits 50, secured at either end to

headers 51 and 52. The lower header 52 is supplied with a refrigerant in a liquid state from a container 54, mounted along the upper side of the reservoir above header 51, by means of a vertically extending supply conduit 56. The upper header 51 receives the refrigerant in a gaseous state after it has passed from the lower header 52 up through conduits 50. From the upper header 51, the gaseous refrigerant is passed through conduits 56a, a compressor, condenser and expansion valve (none of which are shown) and transformed back into a liquid state and returned to container 54a, and through conduits 54b to container 54, where the cycle will again be repeated. The liquid refrigerant supplied to lower header 52, through conduit 56, is controlled by a conventional float valve 57 mounted within container 54.

Mounted within the modified form of reservoir 48 are a plurality of spaced, vertically extending flow-guiding, ice-forming baffle members 58 and a single vertically extending ice-forming baffle member 60 having its vertical plane at a right angle to that of the spaced baffle members 58 and adapted to separate said members 58 into substantially equal sections. The arrangement of baffle members 58 and baffle member 60 causes the circulating liquid to flow in a substantially vertical plane and alternately from one section of baffle members to the other. The vertical conduits 50 and 56 and headers 51 and 52 are secured to one side of the ice-forming baffle members 58, as seen in FIG. 6.

A plurality of fin-like louver members 62 are mounted on either side of baffle members 58 and angularly extend therefrom into the space formed intermediate adjacent baffle members. The fin-like members extend from the baffle members so that they are pointing in a direction substantially contra to the flow of the circulating liquid and likewise cause turbulence of said liquid, thereby increasing the heat transfer from the liquid to the refrigerant circulating in the vertical conduits 50.

When the demand on the cooling system is small, that is to say, when the aforementioned cans or receptacles are removed from the cooling tank 65, the amount of heat carried by the circulating liquid is small, resulting in the liquid adjacent the vertical conduits 50 congealing. Upon increase of the demand of the cooling system, the circulating liquid causes the congealed liquid to gradually melt away, thereby effecting greater cooling of the circulating liquid. The liquid circulating in reservoir 48 also congeals about the cooling coils and between the adjacent fins when the cooling demand is reduced.

The water circulation between the reservoir 48 and the cooling reservoir or tank 65 is from the reservoir through the pipe 66 to the tank and from the tank through the pump 10a and pipe 67 to the reservoir 48. In general, when the cans are in the tank 65, ready to be cooled by the cooling water from the melting ice in the reservoir, the pump 10a is started to effect circulation of water through the tank 65 between the baffles 16, 18 and 20. At the beginning of the circulation of cooling water, the ice formation on the baffles may be flush with the plane of the outer edges of the fins 62. Under these conditions the flow through the passages between the baffles is comparatively unimpeded and not subjected to great turbulence. This smooth, uninterrupted, nonturbulent flow would continue as the ice continued to melt were it not for the turbulence-creating flow-obstructing fins 62. With the turbulence-creating flow-obstructing fins functioning, the effective cross-sectional area of the flow channels is not changed by the melting of the ice as the ice-melting water has to flow through the bottlenecks between the adjacent edges of opposed fins projecting from the baffles.

The construction and use of applicant's easily installed flow-agitating ladder-like construction will now be described.

In general, under certain conditions and under certain situations, it may not be necessary to use any of the louver constructions 62, using only as many of the agitating

lattice or ladder bars as are necessary to effect the proper temperature control.

The liquid-agitating ladder or lattice construction shown in FIG. 8 comprises a series of parallel agitating bars 73 secured to the upright beams 74, which beams are provided with hooklike formations 75 at their upper ends for hooking over the headers 51 depending from the conduits 56 and 56a connecting the headers with the gas-containing chambers 54a and 54.

FIGS. 9, 10, 11 and 12 show different positions which a certain type of foldable lattice-like control bar construction may assume in process of assembly, for example, for use in a tank like that of FIGS. 6 and 7.

FIG. 9 shows the sections unfolded so as to occupy substantially a flat planar position when installed in the tank.

FIG. 10 shows the position which this foldable construction may assume when folded into compact zigzag formation—perhaps for use in shipment or perhaps for assembly in position above a reservoir or tank of the type of FIGS. 6 and 7 for enabling the zigzag formation to be straightened out and lowered into the tank.

FIG. 11 shows the position which the lattice-like construction may assume when inserted into the tank in vertical position between the cooling plates or baffles and suspended from supporting bars at the upper end of the tank.

FIG. 12 is a diagrammatic plan view of the construction shown in FIGS. 6 and 7 with the eight lattice members suspended in the tank.

FIG. 9 shows the unfolded extended ladder or lattice sections, each section comprising a pair of substantially parallel links 76 overlapping at their joints, the overlapping joints being hinged together and to the cross bars 73 by suitable pivotal connections 77 so that the lattice work can be folded from the extended position shown in FIG. 9 to the collapsed zigzag position shown in FIG. 10. The upper links are twisted at 78 and provided with openings 79 to receive supporting rods 80 which extend above the ice builder tank 81 and are inserted into openings in the supporting brackets 82 which are mounted on the upper portion of the tank 81, as shown in FIGS. 11 and 12. Fins 62 similar to those shown in FIGS. 6 and 7 may be provided on the baffle construction 58 if desired.

After the lattice construction has been folded or stacked as shown in FIG. 10, the assembly is placed on top of the tank and unfolded therefrom from the bottom by

lowering the section into the tank between the refrigerating coils. After the assembly has been thus unfolded and lowered into the ice-building tank, the supporting rods 80 are inserted through the openings 79 in the upper sections of the ladder and mounted on suitable supports at the upper portion of the tank.

The cross-section of FIG. 5a is substantially the same as that shown in FIG. 8 except that chain sections 83 are substituted for the upright beams 74 of FIG. 8, flat bars 84 are substituted for the round bars 73 and welded to the chains 83, and hooks 85 are welded to the upper bar 84. These flexible chain sections enable ready installation of the lattice work construction when installing in cramped quarters.

Further modifications will be apparent to those skilled in the art and it is desired, therefore, that the invention be limited only by the scope of the appended claim.

Having thus described my invention, what I claim and desire to secure by Letters Patent is:

20 A freezing and ice-melting cooling apparatus comprising a refrigerant-receiving and heat-transferring device provided with an extensive heat transfer surface, a flow guide having an extensive liquid flow guide surface parallel to said heat transfer surface, and means for causing a flow of congealable liquid in the passage between said surfaces, whereby the liquid may be congealed on said heat transfer surface by the refrigerant and may be melted therefrom by the flow of the liquid, said surfaces being provided with a series of bars extending across the 25 passage intermediate said surfaces and substantially parallel to each other and to said surfaces to increase the turbulence of water passing through said passage, said bars having connections therebetween adjacent their ends extending in the direction of liquid flow to form, with 30 said bars, a rectangular lattice, said lattice having readily detachable hook means adjacent one end for supporting the lattice in position in said passage.
